United States Patent Office

Des. 209,130
Patented Nov. 7, 1967

209,130

BRUSH

Ronald Edwin Brookes, Bath, England, assignor to L. G. Harris & Company Limited, Worcestershire, England, a British company

Filed Oct. 13, 1966, Ser. No. 4,265

Claims priority, application Great Britain Apr. 15, 1966

Term of patent 14 years

(Cl. D9—2)

FIG. 1.

FIG. 2.

FIG. 3.

FIG. 4.

FIG. 5.

FIG. 6.

FIG. 7.

FIG. 8.

FIGURE 1 is a top perspective view showing one end and one side of a brush embodying my new design;

FIGURE 2 is a top plan view thereof;

FIGURE 3 is a bottom perspective view, thereof, showing the opposite side and opposite end;

FIGURE 4 is a side elevational view thereof;

FIGURE 5 is an end elevational of the brush looking in the direction of the arrow V indicated in FIGURE 4;

FIGURE 6 is an end elevation looking in the direction of the arrow VI indicated in FIGURE 4;

FIGURE 7 is a vertical, longitudinal section taken on the line VII-VII of FIGURE 5; and

FIGURE 8 is a vertical, transverse section taken on the line VIII-VIII of FIGURE 4.

I claim:

The ornamental design for a brush, as shown.
